UNITED STATES PATENT OFFICE.

WILLIAM PATRICK HILLEY, OF DES MOINES, IOWA.

OPERATING DEVICE FOR WINDOW-SASHES.

1,329,178.

Specification of Letters Patent. Patented Jan. 27, 1920.

Application filed December 11, 1918. Serial No. 266,223.

To all whom it may concern:

Be it known that I, WILLIAM P. HILLEY, a citizen of the United States, and a resident of Des Moines, in the county of Polk and State of Iowa, have invented a new and Improved Operating Device for Window-Sashes, of which the following is a full, clear, and exact description.

The invention relates to windows having upper and lower sashes adapted to be moved up or down into open or closed position.

The object of the invention is to provide a new and improved operating device for window sashes arranged to permit of conveniently raising or lowering the sashes at the will of the operator and locking the sashes in the adjusted positions. Another object is to permit of easily and quickly removing the sashes from the window frame for cleaning, repairs or other purposes. Another object is to dispense with the sash cords and sash weights, such as are now generally used for counterbalancing the sashes.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a front elevation of a window provided with the improved operating device for supporting, raising, or lowering the sashes, parts being shown in section;

Fig. 2 is an enlarged sectional plan view of the operating device as applied;

Fig. 3 is a sectional side elevation of the same on the line 3—3 of Fig. 2;

Fig. 4 is a similar view of the same on the line 4—4 of Fig. 2;

Fig. 5 is a perspective view of the locking plate for the drums; and

Fig. 6 is a front elevation of the hand wheel for turning the operating shaft, parts being shown in section on the line 6—6 of Fig. 2.

The lower and upper sashes 10 and 11 of a window are mounted to slide up and down in the usual guideways 12 and 13 arranged on the sides 14 and 15 of a window frame 16 of usual construction. The sashes 10 and 11 are supported on flexible supports 20 and 21, preferably in the form of steel bands, chains,

cables or the like. Each of the flexible supports 20 and 21 is fastened at one end by suitable fastening devices 22 such as nails, screws and the like, to the side 15 of the window casing, and each flexible support 20 and 21 extends through grooves 23 formed in the sides and bottom of the corresponding sash 10 or 11. The lower corners of the sashes 10 and 11 are provided with friction rollers 24 around which pass the supports 20, 21, as plainly indicated in Fig. 1. The right hand sides of the flexible supports 20, 21 pass over guide pulleys 25, 26 journaled in a suitable bracket 27 attached to a detachable portion 28 forming part of the side 14 of the window frame 16, as plainly illustrated in the drawings. This detachable portion 28 is of a height exceeding that of a sash and is of a width corresponding to that of both sashes 10 and 11, as plainly shown in Fig. 2. The detachable portion 28 is preferably provided with beveled sides fitting correspondingly shaped walls of an opening 29 formed in the side 14 and normally closed by the detachable portion 28. The detachable portion 28 can be moved into the hollow side 14 whenever it is desired to remove the sashes from the window casing for repairs or other purposes, as hereinafter more fully explained.

The flexible supports 20 and 21 extend from the guide pulleys 25 and 26 to the right and wind and unwind on drums 40 and 41 mounted to rotate loosely on a drum shaft 42 having a detachable extension in the form of an operating shaft 43 provided at its forward end with a polygonal portion 44 extending through a bearing or bushing 45 formed in the front 46 of the side 14 of the window frame or casing 16. The operating shaft 43 is made hollow and through it extends a screw rod 47 having its inner threaded end 48 screwing into the forward end of the drum shaft 42 to couple the shafts 42 and 43 together. The outer end of the screw rod 47 is provided with a handle 49 abutting against the outer end of the polygonal portion 44 of the operating shaft 43 at the time the screw rod 47 is screwed up to couple the shafts 42 and 43 together. The rear portion of the drum shaft 42 is mounted to turn and to slide in bearings 50, 51, of which the bearing 50 is attached to the side 14 of the window frame. The shaft 43 is mounted to turn and to slide in bearings 52 and 53, of which the bearing 52 is attached to the side 14. In

practice, the bearings 51 and 53 are attached to or form part of a bracket 54 secured to the detachable portion 28. On the shaft 42 intermediate the drums 40 and 41 is secured 5 a coupling member 55, preferably in the form of a toothed wheel and provided on the rear face with coupling pins 56 adapted to engage coupling recesses 57 in the front face of the drum 41, and the front face of 10 the coupling member 55 is provided with coupling pins 58 adapted to engage recesses 59 formed in the rear face of the drum 40. Thus on moving the shaft 42 lengthwise the coupling member 55 can be moved in engagement 15 with the drum 40 or with the drum 41 according to which of the sashes 10 or 11 is to be raised or lowered at the time. Thus, as shown in Fig. 2, the pins 56 of the clutch member 55 are in engagement with the drum 20 41 and when the shaft 42 is rotated in one direction then the support 21 is wound up on the drum and consequently the upper sash 11 is raised, and when the shaft 42 is turned in the opposite direction then the 25 flexible support 21 unwinds from the drum 41 thus producing a slack in the flexible support 21 and thereby allowing the sash 11 to slide downward by its own weight. When the shaft 43 is drawn forwardly by the operator having hold of the handle 49 then the pins 56 of the clutch member 55 disengage the drum 41, and the pins 58 of the clutch member 55 then engage the recesses 59 of the drum 40 to allow of turning the latter 30 35 for raising or lowering the lower sash 10 according to the direction in which the shaft 42 is turned.

In order to permit of conveniently turning the driving shaft 43 and with it the 40 drum shaft 42, use is made of a wheel 60 having its hub 61 provided with a polygonal bore 62 through which extends the polygonal part 44 of the shaft 43. The hub 61 is provided with a toothed wheel 63 engaging 45 a bearing 64 formed in the back of a plate 65 secured to the face of the front 46 of the casing side 14. An extension handle 66 is mounted to slide in a bearing in the wheel 60 and the handle is provided with a slot 67 50 through which extends a pin 68 held on the wheel 60. By the arrangement described the handle 66 may be moved outward into extended position, as indicated in dotted lines in Fig. 6, to permit of conveniently turning 55 the wheel 60 and with it the shaft 43 coupled to the shaft 42 to rotate the latter for winding up or unwinding the corresponding flexible support 20 or 21, as above explained. The toothed wheel 63 is adapted to be engaged 60 by a locking bolt 69 mounted to slide in the bearing 65 and serving to normally lock the said toothed wheel 63 and the hand wheel 60 to prevent accidental turning of the shafts 43 and 42.

65 In order to lock the drum 40 or the drum

41 or both against rotation at the time the pins 57, 58 are out of engagement with the drums 41, 40, the following arrangement is made: The drums 40 and 41 are provided with toothed locking wheels 70, 71 adapted 70 to be engaged by the ends 72, 73 of a locking plate 74 mounted to slide transversely in guideways 75 formed in the bearings 53, 51. The plate 74 is provided at or near its middle with a fork 76 straddling the clutch 75 member 55 so that when the latter is shifted transversely on shifting the drum shaft 42 as previously explained then a like transverse sliding motion is given to the locking plate 74 to move the ends 72, 73 thereof in 80 or out of engagement with the toothed wheels 70, 71. When the several parts are in the position shown in Fig. 2 then the drum 41 is coupled with the shaft 42 to rotate with the same and the end 73 of the 85 locking plate 74 is now out of engagement with the toothed wheel 71 of the drum 41 while the other end 72 of the locking plate 74 is in engagement with the toothed wheel 70 of the drum 40 to hold the latter against 90 rotation while the drum 41 is free to rotate on turning the handle 66 for raising or lowering the upper sash 11, as above explained. When the shaft 42 is moved forwardly to couple the shaft with the drum 40, as previously explained, then the end 72 of the locking plate 74 moves out of engagement with the toothed wheel 70 while the end 73 of the locking plate 74 moves into engagement with the toothed wheel 71 to hold the 95 latter against rotation while allowing turning of the drum 40 for raising or lowering the lower sash 10.

The sashes 10 and 11 are adapted to be locked in place in whatever position they 100 may be in at the time and for this purpose the following arrangement is made: The clutch member 55, as previously stated, is in the form of a toothed wheel in mesh with a rack 80 mounted to slide in a bearing 81 110 forming part of the bracket 54. The rack 80 is provided at its left-hand end with a pivot 83 on which is mounted a crossbar 84 connected at its ends with bolts 85, 86 terminating in heads 87, 88 adapted to engage the 115 right hand stiles of the sashes 10 and 11 to lock the latter in place. The heads 87, 88 are mounted to slide in the bracket 27 carrying the guide rollers 25, 26 previously mentioned (see Figs. 2 and 3). It will be noticed that 120 when the shafts 42 and 43 are moved forwardly by the operator having hold of the handle 66 then the coupling member 55 can be moved into neutral position, that is, out of coupling engagement with the drums 125 40 and 41. The coupling member 55 in its neutral position is in mesh with the rack 80, and the operator on swinging the handle 66 upward causes the rack 80 to move from the right to the left thus pushing both heads 130

87, 88 of the bolts 85, 86 into firm contact with the sashes 10 and 11 to hold the latter locked in the position they may be in at the time.

5 When it is desired to remove the sashes 10 and 11 from the window casing 16 for cleaning, repairs or other purposes then the operator first moves the sash 10 or 11 to lower-most position and then takes hold of the 10 hand wheel 49 and draws the same forward to its full extent, that is, until the pins 58 of the clutch member 55 engage the recesses 59 of the drum 40. The shaft 42 in this forward position is disengaged from the bearing 15 50 and engages both bearings 51 and 53. The shaft 43 is now detached from the shaft 42 by the operator turning the hand wheel 49 to unscrew the screw rod 47 from the shaft 42 and to allow of moving this shaft 20 43 out of engagement with the shaft 42. The operator now detaches the portion 28 from the side 14 thus allowing the right hand side of the sashes 10 or 11 to be moved into the opening 29 of the side 14 with a view to 25 allow disengaging of the left hand side of the corresponding sash 10 or 11 from the corresponding guideway at the side 15 and to allow of swinging the released left side of the sash 10 or 11 forward until it clears the 30 front of the window casing. When this has been done, the operator by pulling the corresponding sash 10 or 11 from the right to the left disengages the same from the opening 29. It will be noticed that during this manipulation of the sashes 10 and 11 they are 35 freed of the flexible supports 20 and 21 and the sashes after being removed can be cleaned or repaired as the case may be.

The flexible supports 20 and 21 if in 40 the form of sprocket chains pass around sprocket drums which when rotated cause the sprocket chains to raise and lower the sashes as above explained.

Having thus described my invention, I 45 claim as new and desire to secure by Letters Patent:—

1. An operating device for window sashes, comprising flexible supports, one supporting an upper sash and one supporting a lower sash, one end of each support being fixed to the window casing, each support extending along the sides and bottom of the corresponding sash to support the same, drums on which wind and unwind the 50 other ends of the said supports, a drum shaft mounted to slide and on which the drums are mounted to rotate loosely, a coupling having coupling members on the said drums and having a coupling member fixed on the 55 drum shaft between the drums and adapted to engage either of the coupling members on the drums to rotate the coupled drums on turning the drum shaft, and a drum locking device controlled by the said drum shaft 60 and adapted to alternately lock the drums on 65

moving the coupling member on the drum shaft out of engagement with the coupling members on the drums.

2. An operating device for window sashes, comprising flexible supports, one 70 supporting an upper sash and one supporting a lower sash, one end of each support being fixed to the window casing, each support extending along the sides and bottom of the corresponding sash to support the same, 75 drums on which wind and unwind the other ends of the said supports, a drum shaft mounted to slide and on which the drums are mounted to rotate loosely, a coupling having coupling members on the said drums and 80 having a coupling member fixed on the drum shaft and adapted to engage either of the coupling members on the drums to rotate the coupled drums on turning the drum shaft, and a sash locking device adapted 85 to engage the sashes to lock them against movement, the said locking device being controlled by the said shaft.

3. An operating device for window sashes, comprising flexible supports, one 90 supporting an upper sash and one supporting a lower sash, one end of each support being fixed, each support extending along the sides and bottom of the corresponding sash to support the same, drums on which 95 wind and unwind the other ends of the said supports, a drum shaft mounted to slide and on which the drums are mounted to rotate loosely, a coupling having coupling members on the said drums and having a 100 coupling member fixed on the drum shaft and adapted to engage either of the coupling members on the drums to rotate the coupled drums on turning the drum shaft, locking members adapted to engage the 105 sashes to lock the same against movement, a rack on which the said locking members are attached, and a gear wheel forming part of the said coupling member on the drum shaft and adapted to mesh with the 110 said rack at the time the drum shaft coupling member is out of engagement with the coupling members on the drums.

4. An operating device for window sashes, comprising flexible supports, one 115 supporting an upper sash and one supporting a lower sash, one end of each support being fixed, each support extending along the sides and bottom of the corresponding sash to support the same, drums on which 120 wind and unwind the other ends of the said supports, a drum shaft mounted to slide and on which the drums are mounted to rotate loosely, a coupling having coupling members on the said drum and having a coupling member fixed on the drum shaft and adapted to engage either of the coupling members on the drums to rotate the coupled drums on turning the drum shaft, an operating shaft, means detachably connecting 125 130

the operating shaft with the said drum shaft, and means on the said operating shaft for shifting the shafts lengthwise.

5. An operating device for window sashes, comprising flexible supports, one supporting an upper sash and one supporting a lower sash, one end of each support being fixed, each support extending along the sides and bottom of the corresponding sash to support the same, drums on which wind and unwind the other ends of the said supports, a drum shaft mounted to slide and on which the drums are mounted to rotate loosely, a coupling having coupling members on the said drum and having a coupling member fixed on the drum shaft and adapted to engage either of the coupling members on the drums to rotate the coupled drums on turning the drum shaft, an operating shaft, means detachably connecting the operating shaft with the said drum shaft, and means on the said operating shaft for shifting the shafts lengthwise and connecting or disconnecting the shafts.

25 6. An operating device for window sashes, comprising flexible supports, one supporting an upper sash and one supporting a lower sash, one end of each support being fixed, each support extending along the sides and bottom of the corresponding sash to support the same, drums on which wind and unwind the other ends of the said supports, a drum shaft mounted to slide and on which the drums are mounted to rotate loosely, a coupling having coupling members on the said drums and having a coupling member fixed on the drum shaft and adapted to engage either of the coupling members on the drums to rotate the coupled drums on turning the drum shaft, an operating shaft, means detachably connecting the operating shaft with the said drum shaft, and means on the said operating shaft for shifting the shafts lengthwise, a hand wheel slidably engaged by the said operating shaft and adapted to turn the latter, and a fixed bearing in which the said hand wheel is mounted to turn.

7. An operating device for window sashes, comprising flexible supports, one supporting an upper sash and one supporting a lower sash, one end of each support being fixed, each support extending along the sides and bottom of the corresponding sash to support the same, drums on which wind and unwind the other ends of the said supports, a drum shaft mounted to slide and on which the drums are mounted to rotate loosely, a coupling having coupling members on the said drums and having a coupling member fixed on the drum shaft and adapted to engage either of the coupling members on the drums to rotate the coupled drums on turning the drum shaft, an operating shaft, means detachably connecting the operating

shaft with the said drum shaft, means on the said operating shaft for shifting the shafts lengthwise, a hand wheel slidably engaged by the said operating shaft and adapted to turn the latter, a fixed bearing 70 in which the said hand wheel is mounted to turn, and locking means on the bearing adapted to engage the hand wheel to lock the latter against turning.

8. In a window, upper and lower sashes, 75 a window frame in which the sashes are mounted to slide up and down, the window frame having at one side a removable portion exceeding the heights and widths of the sashes, the said portion when removed allowing the sashes to pass into the opening left by the removed portion, and an actuating device for the said sashes and mounted on the said removable window frame portion to move bodily with the same on removing 80 the said window frame portion, said actuating device including a sliding shaft made in sections, and means for detachably connecting the sections of the shaft.

9. In a window, upper and lower sashes, 90 a window frame in which the sashes are mounted to slide up and down, the window frame having at one side a removable portion exceeding the heights and widths of the sashes, the said portion when removed 95 allowing the sashes to pass into the opening left by the removed portion, an actuating device for the said sashes and mounted on the said removable window frame portion to move bodily with the same on removing 100 the said window frame portion, and an operating device detachably connected with the said actuating device.

10. In a window, upper and lower sashes, a frame in which the sashes slide having at 105 one side a removable portion exceeding the heights and widths of the sashes, and an actuating device for the sashes mounted on the removable portion of the frame, said actuating device including a sliding and rev- 110 oluble shaft having a detachable extension, means for connecting the said extension with the shaft, said means serving to slide the shaft and its extension, and means carried by the extension for revolving the said 115 shaft.

11. In a window, sashes, flexible supports for the sashes, a sliding and revoluble shaft, drums loosely mounted on the shaft and upon which the flexible supports are wound, and 120 a member fixedly secured to the shaft between the drums and having means for engaging the drums to cause them to turn therewith.

12. In a window, sashes, flexible supports 125 for the sashes, a sliding revoluble shaft, drums loosely mounted on the shaft and upon which the flexible supports are wound, said drums being provided with recesses in their opposing faces, and a member fixedly 130

secured to the shaft between the drums and having pins on its faces to engage the recesses of the drums.

13. In a window, sashes, flexible supports for the sashes, a sliding and revoluble shaft, drums loosely mounted upon the shaft upon which the flexible supports are wound, toothed wheels carried by the drums, a member fixedly secured upon the shaft between the drums, and having means for engaging the drums to cause them to turn therewith, and a locking member operated by the said fixed member for alternately moving it into engagement with the toothed wheels.
14. In a window, sashes, flexible supports for the sashes, a sliding and revoluble shaft, drums loosely mounted on the shaft and upon which the flexible supports are wound,

toothed wheels carried by the drums, a member fixedly secured to the shaft between the drums and having means for engaging the drums to cause them to turn therewith, and a sliding locking member having a fork straddling the said fixed member.

15. In a window, sashes, flexible supports for the sashes, a sliding and revoluble shaft, drums loosely mounted on the shaft and upon which the flexible supports are wound, a toothed wheel fixedly secured to the shaft between the drums and having means for engaging the drums to cause them to turn therewith, a rack meshing with the toothed wheel, and bolts carried by said rack for locking the sashes.

WILLIAM PATRICK HILLEY.
